[57] CLAIM

The ornamental design for an immobilization brace, as shown and described.

DESCRIPTION

FIG. 1 is a front, top and left side perspective view of an immobilization brace showing our new design; FIG. 2 is a rear, top and right side perspective view thereof; FIG. 3 is a front, top and left side perspective view of an alternate form of the immobilization brace of our design; FIG. 4 is a rear, top and right side perspective view thereof; FIG. 5 is a top plan of the immobilization brace of FIGS. 1 and 2; and

FIG. 6 is a top plan of the immobilization brace of FIGS. 3 and 4.

The bottom of the immobilization brace is unadorned.
